Cyrus N. Goldstein
ATTORNEY.

UNITED STATES PATENT OFFICE.

WILLIAM ISRAEL, OF WILKES-BARRE, PENNSYLVANIA.

LAMP-SUPPORTING ATTACHMENT FOR MINERS' CAPS.

Application filed March 21, 1921. Serial No. 454,047.

To all whom it may concern:

Be it known that I, WILLIAM ISRAEL, a citizen of the United States, and a resident of Wilkes-Barre, in the county of Luzerne and 5 State of Pennsylvania, have invented an Improvement in Lamp-Supporting Attachments for Miners' Caps, of which the following is a specification.

My invention relates to improvements in 10 lamp supporting attachments for miners' caps and it has for one of its objects to provide an attachment of such construction that it is adapted not only to support the various kinds of lamps upon the market and 15 in general use but also to provide means whereby the lamps are held positively in position against swinging movements either laterally or forwardly; and a further object is to provide a construction of attachment 20 which is adapted to prevent the hook by means of which the lamp is attached to and supported upon the attachment from contacting with the cap, and also whereby the 25 possibility of the lamp supporting hook contacting with and injuring the head of the wearer of the cap is prevented.

The said invention consists of a strip of 30 suitable sheet material stamped, molded or otherwise shaped to provide a looped or bent portion which extends horizontally and forwardly with respect to the cap to which it is attached and with respect to an intermediate vertical portion of the said strip a sufficient 35 distance to provide means forwardly of the said intermediate portion for engaging the hook or bracket of a lamp to support the same in spaced relation with respect to the said strip.

In order that my invention may be more 40 readily understood and its practical advantages fully appreciated, reference may be had to the accompanying drawing in which I have illustrated certain embodiments thereof, but it will be understood that changes in the details of construction may be made 45 within the scope of the claims without departing from the said invention.

In the drawing:

Fig. 1 is a perspective view of a device 50 embodying my invention and of the front

portion of a cap to which it is attached;

Fig. 2 is a central vertical sectional view of the said device and of the adjacent portion of the cap to which it is attached;

Fig. 3 is a horizontal transverse sectional 55 view, enlarged, taken on the line 3-3 of Fig. 1;

Fig. 4 is a perspective view showing a modified construction of the device embodying my invention;

Fig. 5 is a horizontal transverse sectional view taken on the line 5-5 of Fig. 4; and

Figs. 6 and 7 are perspective views of the 60 lamps each having different forms of construction of hooks for engaging the lamp supporting attachment on the cap.

Referring to the drawing: 1 designates a miner's cap to which a lamp supporting attachment A is secured.

The lower terminal end portion 2 of the 70 attachment A rests upon and is secured by rivets 3 to the vizor of the cap while the intermediate central portion 2^a thereof occupies a vertical position against or adjacent the front portion of the cap.

3 designates a forwardly extending bent or looped portion formed by extending the strip forward at the upper end of the portion 2^a, as shown at 4, then extending it upwardly and then extending it rearwardly, 80 as shown at 5, a distance well to the rear of the intermediate vertical portion 2^a. The parts 4 and 5 are spaced from each other and are in general or substantially parallel 85 relation to each other. The attachment A is further secured to the cap by means of rivets situated adjacent the rear end of the rearwardly extending portion 5.

Upon reference to Figs. 1, 2 and 4 of the drawing, it will be noted that the portions 90 4 and 5 are arranged in parallel relation to each other and that the said portion 4 extends a considerable distance forwardly from the upper end of the intermediate portion 2^a of the attachment. For the purpose 95 of providing means for supporting and holding lamps upon the attachment, I have provided openings through the parts 4 and 5 for the reception of the hooks upon the lamps, the said openings being in alinement 100

or in registry with each other, as is indicated in Fig. 2. For the purpose of supporting a lamp 10 such as that shown in Fig. 2, having a single hook 11 which is circular in cross section, I have provided the holes 12, one above the other, as shown, through which the depending portion of the hook 11 extends, as is shown in said Fig. 2. To prevent lateral swinging movements of the lamp 10 provided with a single hook of the character shown in Fig. 2 and as above described, I have provided a slot 15 extending transversely of the bend connecting the parts 4 and 5 and terminating at its opposite ends in the T-slots 16, as shown in Figs. 1 to 3 of the drawing. The slots 16 are situated a distance in front of the holes 12 and the slot 15 is situated in vertical alinement with and in front of the said hole. 10 The slots 16 are situated one above the other and are adapted to receive a supporting prong 20, such as is provided upon the lamp 21, shown in Fig. 7. 22 designates slots which are arranged in alinement transversely of the strip constituting the attachment A in alinement with the slots 16. The holes or slots 22 of the respective couples are arranged one above the other as shown and are adapted to receive the prong 23 of the lamp 24 shown in Fig. 6 to support the latter. It will be observed that when the prongs 20 and 23 are inserted through the vertically arranged slots or openings provided therefor, the lamps or lights 21 and 24 are positively supported against swinging or vibratory movements of any kind or character, due to the movement of the cap as the wearer of the cap may sway or move his head in one direction or another. 20 In Fig. 5 the slot 15 terminates in relatively long T-slots 25 which are arranged one above the other, as is indicated in Figs. 4 and 5. The single slot 25 is of a length equal to the distance between the outer edges 45 of the slots 22 shown in the previous figures and is adapted to receive prongs such as those shown at 23 for supporting a lamp and is also adapted to receive a single prong of a width equal to the length of the said slots. Such a slot, however, is not adapted to receive a relatively narrow prong such as 50 20, because it would permit lateral swinging or movement of the lamp. 55 When a construction of attachment such as that shown in Figs. 1, 2 and 3 is employed, I propose to provide the said attachment with a supporting loop, such as 26, shown in Figs. 1 and 2, which is adapted to receive a relatively wide prong similar to that previously referred to as adapted to enter the relatively long T-slots 25. 60 In the construction as shown it will be observed that the prongs of the hooks or similar supporting means attached to the lamps which pass through the openings 12, 16, 22

or 25 terminate at a point forwardly of the central intermediate portion of the attachment, in consequence of which said central intermediate portion of the attachment constitutes a shield or protective device to prevent the end of the hook or other similar prong from contacting with the head of the wearer. Furthermore, by providing the attachment with the overhanging projecting portion through which the openings 12, 16, 22 and 25 extend, I am enabled to support the lamps a distance from the cap and consequently a greater distance than usual from the head of the wearer, which is very desirable because in actual use these lamps become quite warm and create discomfort for the wearer. In the case of my construction, however, where the lamp as shown in Fig. 2 is supported in position a considerable distance from the front part of the cap, free circulation of air is provided, thereby preventing the cap from becoming heated sufficiently to render the wearing thereof a discomfort. 70 80 85 90 95 100 105 110 115 120 125 130

Having thus described my invention, what I claim and desire to secure by Letters Patent is:

1. A lamp supporting attachment consisting of a strip of suitable material adapted to be attached to the front portion of a cap, the said strip comprising a central intermediate portion which is adapted to be situated adjacent the front part of the cap, and an overhanging portion projecting a substantial distance forwardly of the said intermediate central portion, the said overhanging portion comprising parallel portions of the said strip spaced from each other, and openings through the said parallel portions of strip arranged one above the other, the said openings being adapted to receive prongs attached to lamps for supporting the latter. 105 110 115 120 125 130

2. A lamp supporting attachment for miner's caps comprising a strip of suitable material which is attached to the front portion of a cap, the said strip having a central intermediate portion which is situated adjacent the front part of the said cap, the said strip extending forwardly in a horizontal direction from the upper end of the said central portion a substantial distance, then upwardly and rearwardly to a point in rear of the said central intermediate portion, thus forming parallel spaced portions in front of the plane of the said central intermediate portion, the said parallel portions having a plurality of openings extending therethrough, the said openings being arranged in couples and the openings of each couple being arranged one above the other, and the said openings being adapted to receive lamp supporting prongs of different shapes in transverse section. 130

3. A lamp supporting attachment consisting of a strip of suitable sheet material

adapted to be attached to the front portion of a miner's cap the said strip comprising forwardly projecting parallel spaced portions at the upper end portion thereof the 5 said portions having a plurality of couples of openings therethrough for the reception of the supporting hooks of miners' lamps

and the holes of each couple being arranged in alignment with each other.

In testimony that I claim the foregoing 10 as my invention, I have hereunto subscribed my name this 15th day of March, 1921.

WILLIAM ISRAEL.
